UNITED STATES PATENT OFFICE.

JOHN B. RIEG, OF ORANGE, MASSACHUSETTS, ASSIGNOR TO ERVING PAPER MILLS, OF ERVING, MASSACHUSETTS, A CORPORATION OF MASSACHUSETTS.

DESIGN FOR EMBOSSED PAPER FOR PAPER NAPKINS OR SIMILAR ARTICLES.

Application filed August 10, 1928. Serial No. 27,780. Term of patent 14 years.

To all whom it may concern:

Be it known that I, JOHN B. RIEG, a citizen of the United States, residing at Orange, in the county of Franklin, and State of Massachusetts, have invented a new, original, and ornamental Design for Embossed Paper for Paper Napkins or Similar Articles, Such as Paper Doilies, Paper Table Covers, Paper Tray Covers, or Paper Wrappings for Packages or Boxes, of which the following is a specification, reference being had to the accompanying drawing, forming a part thereof.

The figure is a face view of an embossed

sheet of paper for paper napkins or similar articles, showing a complete repeat unit of the design with sufficient detail of adjacent repeat units to indicate the connection between them. It will be understood that these units are repeated over the entire surface to be ornamented.

I claim:

The ornamental design for embossed paper for paper napkins or similar articles, substantially as shown and described.

JOHN B. RIEG.
